AUTOMATIC CONTROL OF CENTRIFUGAL DEVICES

Charles A. Olcott, Montclair, N. J.

Application April 2, 1936, Serial No. 72,390

8 Claims. (Cl. 210—72)

This invention relates to control means for centrifugal machines such as are used in drying and washing sugar and similar solids and it is an object of the invention to provide means for automatically controlling operations of such machines. It is a further object of this invention to provide such a means that its operation will be started upon completion of the loading of the basket of the centrifugal machine with material to be treated.

In the drawing—

Fig. 1 is a diagrammatic view illustrating a preferred form of this invention; and

Fig. 2 is a view in elevation of the operating parts of a timing mechanism used.

In the drawing there is shown a perforated basket 1 of a centrifugal machine driven through shaft 2 by a motor 3 having a rotor 4. The motor is usually a multi-phase alternating current motor but for the sake of clearness there is shown in the drawing but one phase of the usual power circuit. The stator of the motor is provided with a high speed winding 6 and a low speed winding 8 in order that the motor may operate the basket 1 at different speeds. Fixed on the shaft 2 is a brake drum 10 arranged to be engaged by a brake shoe 12 and positioned above the basket 1 is the loading spout 14, the discharge from which is controlled by a gate 16 operated by a lever or handle 18.

Current for the low speed operation of the motor 4 is supplied from the lead L¹ of the line through leads 20 and 22 to the contacts of a switch PB—2, when the switch is operated against the action of a spring, lead 23 to the low speed winding 8, leads 24 and 25 to switch SW—1 and leads 26, 27 and 28 to the lead L² of the line. The switch PB—2 is spring-operated to a position in which the contacts of leads 22 and 23 are normally disconnected and contacts of leads 22^a and 23^a are normally connected. Switch PB—2 in its normal position, that is, when not operated manually, establishes communication through the leads 20, 22, 22^a, 23^a to the lead 29 so that when the switch PB—1 is closed current from the line will pass from lead 29 through lead 30 and the contacts of the switch PB—1 to the lead 32 and lead 34 where it divides, part of the current passing through the high speed winding 6 to lead 25 while a part passes through the solenoid 36 of the switch PB—1 and through lead 38 to the lead 25 through which it passes with the current from the high speed winding 6 to the switch SW—1 and through the leads 26, 27 and 28 to the lead L² of the line. The solenoid 36

is provided so that when the switch PB—1 is closed manually against the action of the spring the solenoid is energized and retains the switch closed until the circuit through the high speed winding 6 is opened.

The switch SW—1 is shown as connected to a piston 40 in a cylinder 41 which is operated by air supplied through a valve 42 operated by a solenoid 43, the air being supplied through pipe 44 from suitable source of air pressure and passing through pipe 46 not only to the cylinder 41 but to a cylinder 48 in which is operated the piston 50 which applies the brake shoe 12 to the brake drum 10 so that upon admission of air pressure to the pipe 46 the brake is applied and the switch SW—1 opened to cut off the power to the machine. The valve 42 is a three-way valve which, in its normal position, is opened so as to vent pressure from the cylinders 41 and 48 to the atmosphere but which closes the vent when the valve is operated to supply pressure to the cylinders.

Energization of the solenoid 43 is controlled by a timing device T—1 which comprises a self-starting synchronous motor 52 such as is used in electric clocks, a solenoid 54, which controls the connection between the motor 52 and the movable arm which closes the contacts 56. To control the energization of the motor 52 and solenoid 54 there is provided an extension 18^a on the lever 18 which operates the gate 16 of the filling spout and which extension 18^a is provided at its outer end with an adjustable set screw 58 adapted, when the lever 18 is in its lowermost position, to effect the closure of switch SW—2. The switch is spring-biased to open position, so that while the filling spout is opened the switch SW—2 is opened but upon closure of the filling spout by the gate 16 upon completion of the filling of the basket the switch SW—2 is closed completing a circuit from the lead L¹ through leads 20, 22, 22^a, switch PB—2, leads 23^a and 29 to switch SW—2, lead 60 to the terminals b and c of the timing means T—1. From the terminal c the circuit extends through the limit switch 62 and motor 52 to the terminal a and thence through leads 27 and 28 to the lead L² of the line while from terminal b the current passes through the solenoid 54 to terminal a and thence through the leads 27 and 28 to the lead L² causing the operation of the motor 52 and energization of the solenoid 54.

The timing device T—1 is arranged so that at a predetermined time after the closure of the switch SW—2, starting the motor 52 and energization of the solenoid 54, the contacts 56 will be closed

- completing a circuit from the lead L^1 through leads 20, 22, 22^a, 23, 28 to terminal a , through contacts 56 to the terminal e and thence through the lead 64, solenoid 43 and leads 27 and 28 to the lead L^2 of the line, energizing the solenoid 43.
- 5 For washing the material in the basket suitable washing liquid is supplied from a source of supply through pipe 66, valve 68 and pipe 69 to the spray-head 70, valve 68 being controlled by solenoid 72 which in turn is controlled by the timing device T-2. The timing device T-2, like timing device T-1, comprises a self-starting synchronous motor 52^a and a solenoid 54^a controlling the connection of the motor with the means for operating the contacts 56^a and 56^b. The timing means T-2 is also controlled by the switch SW-2 operated by the handle 18 and upon closure of the switch SW-2 current is supplied from the lead 60 through lead 74 to the terminals b^1 , c^1 and d^1 .
- 10 From the terminal c^1 the current passes through the limit switch 62^a and motor 52^a to the terminal a^1 and thence through leads 76 to lead 28 and the lead L^2 of the line. Current also passes from the terminal b^1 through the solenoid 54^a to the terminal a^1 and thence through leads 76 to the lead L^2 . As was the case with the timing means T-1, operation of the motor 52 causes the operation of the contacts 56^a and 56^b after predetermined times. Contacts 56^a are normally open while contacts 56^b are normally closed so that upon closing of the contacts 56^a the circuit is completed from the lead 74 to terminal d^1 , thence through the contacts 56^a and 56^b to terminal e^1 , lead 18 and solenoid 72 to lead 76 and the lead L^2 energizing the solenoid 72 and operating the valve 68 to supply the washing liquid to the spray-head 70.
- 15 After closing the contacts 56^a the motor continues its operation until contacts 56^b are opened. Thus, after being closed a predetermined time the circuit is opened at the contacts 56^b and the solenoid 72 is de-energized, cutting off the supply of wash liquid to the basket and thereby providing the wash liquid for a predetermined period depending upon the positioning of the contacts 56^a and 56^b.
- 20 In both the timing devices the limit switch 62 serves to stop the operation of the motor after a predetermined time beyond that which is necessary for the operation of the contacts 56^a and 56^b.
- 25 A suitable structure of the timing devices for use in this invention is shown in Figure 2, in which means for operating the contacts 56^a and 56^b are shown. In this structure the motor 52, through worm 80, drives a gear 82 fixed on a shaft 84. Loosely mounted on the shaft 84 is an arm 86 having an extension thereon in which is pivoted the dog or pawl 88 arranged to be operated by solenoid 54, when solenoid 54 is energized, to engage the pawl with the teeth of the gear wheel 82 so that the arm 86 will be moved with the gear wheel.
- 30 Loosely mounted on the shaft is an arm 90 on which are the contacts 56^a and a second arm 92 on which are mounted the contacts 56^b. The arms 90 and 92 may be positioned at different distances with respect to the arm 86 so as to vary the time taken by the arm 86 to approach and operate the contacts on the arms, arm 92 being adjusted manually by extension 92^a while arm 90 is adjusted manually by the arm 90^a, the ends of the arms 90^a and 92 serving as pointers on a graduated scale to indicate the time required for the operating arm 86 to approach and operate the contacts. To operate the contacts the arm 86 is provided with a pin 86^a adapted to engage the

contacts 56^a and close these contacts after a predetermined period of operation depending upon the distance of the contacts from the arm 86 when in normal position. The arm 90 is thereupon moved with the arm 86, and projection 90^b of the arm 90 after a predetermined period engages with the extension of one of the contacts 56^b and separates these contacts thereby opening the circuit which was closed when the contacts 56^b were brought together. While the showing of Figure 2 is applicable to the two contacts shown in timing means T-2 it will be appreciated that the timing means T-1 comprises only one set of contacts 56 which correspond to the contacts 56^a of the timing means T-2. Upon de-energization of the solenoid 54 the pawl 88 is disengaged from the gear 82 and springs return the arms 86, 90 and 92 to their initial positions.

35 Where desired a switch PB-3, spring-pressed to open position, may be provided to establish connection through leads 100 and 102 from lead 29 to lead 64 so that while the motor is in operation at high speed the solenoid 43 may be energized to apply the brake and open the circuit of the motor without waiting for the operation of the timing device T-1. The switch PB-2, it will be noted, controls the circuits of both the low speed and high speed windings of the motor so that when the switch PB-2 is operated to energize the low speed winding of the motor the operation of the switch PB-1 will not energize the high speed winding. It will also be noted that upon release of the switch PB-2 the spring will return it to its normal position, interrupting the circuit of the low speed winding of the motor and completing the circuit to lead 29 so that the brake may be applied by operation of the switch PB-3.

40 In the operation of the device the motor will be started by closing the switch PB-1, solenoid 36 of which thereupon becomes energized and holds the switch closed while the motor is operated at high speed. The gate 16 is then operated by manipulation of the lever 18 to load the basket with the material to be treated. Upon completion of the loading of the basket and the closing of the gate 16 the switch SW-2 is closed completing the circuits for the timing devices T-1 and T-2 causing the motors of these devices to start operating. At a predetermined time after the initiation of the operation of the motor 52^a of timing means T-2 the contacts 56^a are closed, energizing the solenoid 72 to supply the liquid for washing the material in the basket, the time elapsing before the contacts 56^a are closed being determined to provide sufficient time to centrifuge the mother liquor from the material being treated. The solenoid 72 is maintained energized and washing liquid is supplied to the basket until the contacts 56^b are opened whereupon the solenoid 72 is de-energized and the supply of liquid to the basket is cut off. The timing means T-1 is meanwhile operating and upon completion of the washing and centrifuging of the wash liquid from the basket the contacts 56^b are closed energizing the solenoid 43 and supplying air to the cylinders 48 and 41, applying the brake shoe 12 to the brake drum 10 and operating the switch SW-1 to interrupt the circuit of the high speed winding of the motor, decelerating the centrifugal. Upon opening of the motor circuit, solenoid 36 is deenergized and switch PB-1 allowed to open. Where the material is removed from the basket by hand or the bottom of the basket is dropped in order to discharge the dry material therefrom the braking operation will be allowed 75

to continue until the basket has been stopped. Thereupon the lever 18 is operated sufficiently to rest the lever on the shoulder 104 of the bracket 106 which holds the lever raised sufficiently to open the switch SW-2 while the basket is being unloaded but does not raise the gate 16 sufficiently to permit discharge from the filling spout 14 to the basket. Where an unloading device is used and it is desired to operate the motor at a suitable low speed in order to operate the unloading device the lever 18 can be operated when the speed of the motor and basket is sufficiently decelerated so as to open the switch SW-2 and de-energize solenoid 43 to release the brake and the switch PB-2 is operated to close the circuit of the low speed winding, the switch PB-2 being retained closed manually during the unloading operation. Upon removal of the unloading means the switch PB-1 is again closed to operate the basket at high speed and the lever 18 operated to open the gate to load the basket. Upon completion of the loading of the basket the gate 16 is closed causing the switch SW-2 to be closed and initiating the operation of the timing means T-1 and T-2 for another cycle of operations.

While a brake shoe 12 and a brake drum 10 have been shown as the means for decelerating the centrifugal it is to be understood that such showing is for the purpose of illustration only as the piston 50 may be used to operate or control any of the usual braking or decelerating means or systems such as regenerative braking or the reversal of the current to the motor where the motors are equipped for deceleration by such means and that by the expression "means for decelerating" as used in this application is meant all the usual braking or decelerating means or systems.

What is claimed is:

1. The combination with a centrifugal machine having a basket, of manually controlled gate means for loading the basket, means for decelerating said machine, automatic timing means for causing operation of said decelerating means and means for starting said timing means operated by the movement of said gate means to closed position.

2. The combination with a centrifugal machine having a basket, of means for loading the basket, automatic means for effecting washing of the basket contents for a predetermined period and for decelerating said machine and means operated by the movement of said basket loading means to closed position for starting operation of said automatic means at predetermined periods

after the stopping of the loading of the basket by said loading means.

3. The combination with a centrifugal machine having a basket, of means for loading the basket, automatic means for effecting washing of the basket contents for a predetermined period and means operated by the movement of said basket loading means to closed position for starting operation of said automatic means at a predetermined time after the stopping of the loading of the basket by said loading means.

4. The combination with a centrifugal machine having a basket, of gate means for loading the basket, automatic means for effecting washing of the basket contents and means operated by the operation of said gate means to closed position for starting operation of said washing means.

5. The combination with a centrifugal machine having a basket, of gate means for loading the basket, means for washing the basket contents, means for decelerating said machine, automatic timing means for controlling the washing and decelerating means and means operated by the operation of said gate means to closed position controlling operation of said timing means.

6. The combination with a centrifugal machine having a basket arranged for electric motor operation at high and low speeds, means for loading the basket, means for washing the basket contents and for decelerating the machine from high speed, said decelerating means opening the motor circuit for high speed operation, timing means controlling said washing and decelerating means, means operated by the closing of said basket loading means for starting said timing means and means for completing the circuit for low speed operation of the motor.

7. The combination with a centrifugal machine having a basket, of manually controlled gate means for loading the basket, means for decelerating said machine and automatic timing means placed in operation by the movement of said gate means to closed position and causing operation of said decelerating means upon said gate means being held closed for a predetermined period after being closed.

8. The combination with a centrifugal machine having a basket, of manually controlled gate means for loading the basket, means washing the basket contents and automatic timing means placed in operation by the movement of said gate means to closed position and causing operation of said washing means upon said gate means being held closed for a predetermined period after being closed.
